CLAIM

The ornamental design for a thoracic garment, as shown and described.

DESCRIPTION

FIG. 1 is a front elevational view of the thoracic therapy garment of our new design;

FIG. 2 is a rear elevational view thereof;

FIG. 3 is a top plan view thereof;

FIG. 4 is a bottom plan view thereof;

FIG. 5 is an end elevational view of the left end thereof; and,

FIG. 6 is an end elevational view of the right end thereof.

The broken lines in FIGS. 1 and 2 are included for the purpose of illustrating portions of the thoracic therapy garment that form no part of the claimed design.
